DESIGN FOR A BICYCLE FRAME

Earl E. Pease, Oak Park, Ill., assignor to Battery
Patents Corporation, Chicago, Ill., a corpora-
tion of Illinois

Application April 15, 1936, Serial No. 62,140

Term of patent 14 years

To all whom it may concern:

Be it known that I, Earl E. Pease, a citizen of the United States, residing at Oak Park, in the county of Cook and State of Illinois, have invented a new, original, and ornamental Design for a Bicycle Frame, of which the following is a specification, reference being had to the accompanying drawing, forming a part thereof, in which:

Figure 1 is a side elevational view of a bicycle frame, showing my new design; and Fig. 2, a plan view.

I claim:

The ornamental design for a bicycle frame, as shown.

EARL E. PEASE.
